OR D 11,747

No. 11,747

April 27, 1880

UNITED STATES PATENT OFFICE.

WILLIAM C. DAVIS, OF CINCINNATI, OHIO.

DESIGN FOR STOVES.

SPECIFICATION forming part of Design No. 11,747, dated April 27, 1880.

Application filed February 24, 1880. Term of patent 3½ years.

To all whom it may concern:

Be it known that I, WILLIAM C. DAVIS, a citizen of the United States, residing at Cincinnati, in the county of Hamilton and State of Ohio, have invented and produced a new and original Design for Stoves, of which the following is a specification, reference being had to the accompanying illustration, which is a perspective view of the stove.

10 My design is applied to that class of upright cylinder-stoves in which the body is swelled outward between the ends and mounted upon a square or angular base. These stoves are each composed of several distinct castings or 15 parts, susceptible of ornamentation, and to which I have applied my design.

In the accompanying illustration, A is the hearth-plate or bottom of the stove, mounted upon legs B, and supporting the ash-box C and 20 stove-body D.

The corners of the plate A are ornamented with sprays and leaves E, and on the edge molding, between the corners, with cross-lines and sprays F, as shown.

25 The legs at their upper ends are formed with a bead-molding, G, and their faces are marked with sprays, concentric rings inclosing star-like ornaments, and broken lines, all as shown at H.

30 The sides of the ash-box are ornamented with leaves and slender sprays or stalks, as shown at I, and the door in the ash-box is panelled within an ornamental border, J, each panel showing flowers and inclined stems, as shown 35 at K.

The register upon the ash-box consists of a raised rim encircled by a serrated outer-edge line, as shown at L.

The door of the stove-body contains four panels within a frame bearing on its face a series of leaves with cross-bands, as shown at M. The upper panels bear Maltese crosses inclosed by a serrated rim placed above broken lines, as shown at N, and the lower panels are marked with small urns supporting leaves and 45 flowers, as shown at O.

The upper cylindrical section of the stove-body, upon the top of the flange near the edge, is ornamented with short spear-shaped sprigs arranged in groups and pointing toward the 50 top of the stove, as shown at P, and the immediate outer angle of the flange is provided with a beaded molding, Q.

I claim—

1. The design for the bottom plate of the 55 stove, as shown at E F.

2. The design for the stove-legs, as shown at G H.

3. The design for the door of the ash-box, 60 as shown at J K.

4. The design for the stove as a whole, as herein set forth and shown.

In testimony of which invention I have hereunto set my hand this 12th day of February, A. D. 1880.

W. C. DAVIS.
